US00D546157S

(12) **United States Design Patent** (10) **Patent No.:** **US D546,157 S**
Schluter (45) **Date of Patent:** **** Jul. 10, 2007**

(54) **DRIVER BIT**

(75) Inventor: **Robert Schluter**, Kinnelton, NJ (US)

(73) Assignee: **Middle Atlantic Products, Inc.**,
Fairfield, NJ (US)

(**) Term: **14 Years**

(21) Appl. No.: **29/241,775**

(22) Filed: **Nov. 1, 2005**

Related U.S. Application Data

(62) Division of application No. 29/201,779, filed on Mar. 19, 2004, now Pat. No. Des. 513,162.

(51) **LOC (8) Cl.** **08-04**

(52) **U.S. Cl.** **D8/86**

(57) **CLAIM**

The ornamental design for a driver bit, as shown and described.

DESCRIPTION

FIG. 1 is an isometric view of a driver bit showing my new design.

FIG. 2 is a front elevation view of the driver bit of FIG. 1, the rear elevation view being identical.

FIG. 3 is a right side elevation view of the driver bit of FIG. 1, the left side elevation view being identical.

FIG. 4 is a top end view of the driver bit of FIG. 1; and,

FIG. 5 is a bottom end view of the driver bit of FIG. 1.

The portions of the drawings appearing in broken line are for environment only and do not form a part of the design.

1 Claim, 3 Drawing Sheets
